SCREENING AND COOLING CONVEYER

James N. Vandegrift, New York, N. Y., assignor to International Bitumenoil Corporation, New York, N. Y., a corporation of Delaware

Continuation of application Serial No. 345,336, filed March 8, 1929. This application August 14, 1930, Serial No. 475,143

6 Claims. (Cl. 209—307)

This invention relates to conveyers and more particularly to conveyers for removing and at the same time expediting the cooling of coke discharged from a low temperature distillation coal retort.

This is a continuation application of my co-pending application Serial Number 345,336, filed March 8, 1929 for Conveyers.

Coke is discharged from a low temperature distillation retort at approximately 850° F. a temperature sufficient to support combustion if the coke is not properly cooled. It has been found in practice that if coke is permitted to cool to approximately 240° F. before it is collected in a large mass that likelihood of combustion is prevented. Moreover, it has been found that coke cools to such a desired temperature more rapidly if air is permitted to be introduced all around the coke under treatment, while being cooled as contrasted with the introduction of air to the surfaces thereof when resting on a solid support.

An object of the present invention is to provide means for permitting the rapid cooling of coke discharged from a low temperature distillation retort, or other device and for handling any suitable material.

A further object of the invention is to provide means for removing the coke from the retort discharge and for transporting it to the place of collection, while the coke is being cooled.

According to the present invention, the coke is permitted to rapidly cool by discharging the same upon a continuously moving endless conveyer which is moving at a speed slow enough to permit the coke to become cooled during the period between the time of discharge on to the conveyer and the time of discharge from the conveyer. To accelerate the cooling of the coke, the conveyer is so designed and constructed as to permit the introduction of air to all parts of the lumps or mass of coke spread upon the conveyer. Such introduction of air is made possible by providing a raised floor on the conveyer made up of a screen member separated from the solid floor of the conveyer by a space of such dimensions as to permit the ready circulation of air between the respective floors of the conveyer and as a consequence the circulation of air through the coke resting upon the screen.

Other objects and features of this invention will become apparent by reference to the accompanying detailed description of a preferred form of the invention considered in connection with the drawings forming a part of the same, wherein:

Fig. 1 is a side elevation of a conveyer embodying the invention with a portion thereof taken on a section substantially central of the length of the conveyer.

Fig. 2 is a section taken on the line 2—2 of Fig. 1.

Fig. 3 is a section taken on the line 3—3 of Fig. 2.

Fig. 4 is an enlarged vertical section of a modification of the invention.

Fig. 5 is a similar section of a still further modification of the invention.

Referring now to the drawings there is indicated a conveyer embodying the present invention, which conveyer comprises upright supporting members 11 at each end between which extend a pair of horizontal supporting bars 12 in the shape of substantially angle irons. Extending upwardly and inwardly from the supporting bars 12 and from opposite points thereof are a number of supporting members 13 having flat surfaces 14 to the top of which are secured in any desired manner a pair of angle bar rails 15. Depending from the supporting members 12 are a number of hangers 16 to which are secured a pair of angle bar rails 17. These upper and lower rails 15 and 17 serve as tracks for the passage of roller conveyer members joined in such a manner as to permit an endless chain. The construction of the articulated roller conveyer sections is substantially as follows: A number of rollers 18 are connected each to the succeeding one by means of a bar 19. These bars 19 are so connected to the rollers as to permit the same to pass over and around idler and driven wheels.

As shown in Fig. 2, the connecting bars 19 are used in the preferred form in pairs, one pair of bars overlapping the other pair. To each of the innermost connecting bars 19 is secured an inverted L member 20, the projections of which extend inwardly and have secured to the tops thereof a bed plate member 21. Extending upwardly and angularly from each bed plate 21 are side plates 22 provided with a number of openings 23, the purpose of which will be explained herein-after in detail.

As shown in Fig. 3, the forward edge of each bed plate 21 is curved downwardly as at 24 so that the straight rear edge of each bed plate may overlap the front curved edge of the succeeding plate to form a continuous floor. The plates 22, in addition to having a rearward slant, are provided with a vertical portion, more clearly shown at 25. Secured between each of the plates 22 at approximately the point of the end of the vertical

slant and the beginning of the perpendicular portion 25 is a floor member 26 constructed preferably of a screen or some perforated surface. The side plates 22 with their perpendicular portions 25 are of such dimensions that each plate overlaps a portion of the succeeding plate to form a continuous vertical surface preventing the likelihood of any material resting on the supporting surface being discharged between adjacent plates. Of necessity, the screen floor members 26 are of slightly less width than the side plates 22 so that this overlapping may be accomplished.

Mounted at one end of the supporting structure is an idler roller 27, while at the opposite end is mounted a driven sprocket roller 28 for driving the endless chain made up of a number of sections constructed in accordance with the following. The roller 27 is journalled in bearing blocks 29, which blocks 29 are horizontally movable to permit adjustment of the conveyer. This horizontal movement is accomplished by means of nuts 30 passing through an inverted U-shaped member 31 with the respective ends of the nuts 30 resting against the sides of the bearing blocks 29. By loosening or withdrawing one nut 30 and tightening or advancing the other nut, horizontal movement of the block 29 may be occasioned and the same locked in place by the same nuts. A similar construction is provided for the driven sprocket roller 28, similar reference characters with the addition of a prime for each thereof designating similar parts.

The operation of the conveyer in use is substantially as follows: Power to cause rotation of the sprocket roller 28 is supplied by any convenient source, not shown. With the endless chain made up of similar sections as previously described, in movement, which movement is relatively slow, coke is discharged from a low temperature distillation coal retort (not shown) upon the end of the conveyer near the idler roller 27. The coke of necessity falls directly upon the upper floor made up of the successive screen members 26 and these screens 26 may be of such mesh as to permit the so-called "fines" to pass through the screen, coming to rest upon the solid floor made up of successive solid plates 21. The lump coke remains upon the top of the screens 26 to a depth not exceeding the height of the perpendicular portions 25 of the side plates 22. As the conveyer continues its slow movement from the idler roller to the driven roller, air comes into contact with all surfaces of the lump coke remaining upon the screens. Due to the presence of the openings 23 in the side plates 22, it is possible to subject the undersides of the coke to the cooling action of air either in a natural draft or by forced draft.

When the conveyer used is of the type illustrated in Figs. 1 to 3 inclusive it has been found in practice that the length thereof may be materially shortened due to the fact that when the lumps of coke resting on the screens reach the end of normal discharge instead of being dumped from the conveyer they fall in such a manner as to rest upon the under side of the screen in its backward travel and are thereby subjected to further cooling action and finally dumped at the end of the conveyer upon which they are first introduced. This feature is of considerable importance where the space for the conveyer is limited since the time of travel of the material to be cooled can be doubled by letting the lumps of coke travel first on top of the screen through one reach of the conveyer and second travel on what was the bottom of the screen through the second reach

of the conveyer. In any event the fines which cool a great deal more rapidly than the lumps are dumped at the end of the conveyer remote from the point at which they are deposited thereon.

In the event it is desired to cause positive dumping of the lumps at the normal discharge end of the conveyer either one of the modifications illustrated in Figs. 4 and 5 may be utilized. In these modifications all parts of the conveyer are similar with the exception that in Fig. 4 instead of utilizing a screen for the top of the conveyer upon which the coke is to rest use is made of a foraminated plate 51 which has an angular extension 52 serving to cause the positive dumping of the coke from the discharge end of the conveyer. In Fig. 5 use is also made of a foraminated plate 51 which has a vertical right angular extension 53 serving the same purpose as the extension 52.

The operation of the conveyer when made up of these modifications is substantially similar to that previously described with the exception that positive dumping of both the fines and the lump material is assured at the normal discharge end of the conveyer, since the extensions 52 or 53 prevent the lumps from falling onto the normal underside of the plate 51 of any of the various conveyer sections.

It is to be understood that the present invention is capable of modification and while the device has been described as used in connection with the handling of coke it is to be understood that the uses thereof are not to be limited to coke handling since the conveyer operates efficiently for a multitude of purposes. The invention is to be limited only by the scope of the following claims.

I claim:

1. A device of the character described comprising a plurality of similar sections, each having a floor plate, a perforated floor spaced above said floor plate, and a plate extending upwardly from the forward edge of said perforated floor, said sections being joined to form an endless-chain apron conveyer.

2. A device of the character described comprising a series of articulated sections, each composed of a floor plate, side plates, a perforated plate intermediate the said plates and extending over said floor plate, and a perforated plate extending upwardly from the forward edge of said first mentioned perforated plate, said side plates being provided with openings for the circulation of air between the floor plate and the first mentioned perforated plate.

3. A device for cooling lumpy carbonaceous material and conveying same comprising a series of articulated sections arranged as an endless linked conveyer, which sections comprise a perforated plate for receiving the hot material, the perforations in said plate being adapted to permit fines in said material to pass therethrough while retaining lumps thereon, a floor beneath said perforated plate and spaced therefrom and movable therewith for receiving said fines, and side walls for said sections for retaining said lumps of material on said perforated plate and said fines on said floor, the side walls between said floor and said perforated plate being provided with openings for the passage of air therethrough.

4. A device for cooling and conveying coke and the like comprising articulated sections of an endless conveyer having a floor plate, side walls, a perforated plate supported by said side walls and spaced above said floor plate, and openings in said side walls permitting the passage of air.

through said openings over fines on said floor plate and through perforations in said perforated plate and about lumps of material thereon to separately air cool said fines and said lumps.

5. A device for cooling lumpy carbonaceous material and conveying same comprising a perforated receptacle for receiving the hot material in a layer, the perforations in said receptacle being adapted to permit fines in said material to pass therethrough while retaining lumps of said material thereon and for permitting the passage of air upwardly through said perforations, a floor beneath said perforated receptacle and spaced therefrom and movable therewith for receiving the fines, means for moving the said receptacle and floor and means for discharging cooled material from said perforated receptacle and said

floor, said device being apertured so that air from the outside can pass through said perforations in said receptacle and about said lumps thereon to cool said lumps.

6. A device for cooling and conveying coke comprising a travelling screen adapted to receive a thin layer of hot coke, a floor beneath said screen and spaced therefrom and travelling simultaneously with said screen, the side portions between said screen and the floor therebelow being apertured so that air can pass from the outside of said device between said screen and said floor and up through said screen and about coke on said screen to cool fines of coke on said floor and lumps of coke on said screen. 5 10 15
